Primary Examiner — Marianne Pandozzi*(74) Attorney, Agent, or Firm* — Saidman DesignLaw Group, LLC(57) **CLAIM**

The ornamental design for a beverage machine, as shown and described.

DESCRIPTION

FIG. 1 is a perspective view of a beverage machine showing our new design;

FIG. 2 is another perspective view thereof, with a portion of the beverage machine in an open position;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawing depict portions of the beverage machine that form no part of the claimed design.

FIGS. 1-8 include transparent surfaces on the left portion of the claimed design, which are indicated by surface shading and lines that are visible through the transparent surfaces.
